VALVE MECHANISM

J. D. Buchanan, Burbank, Calif.

Original application October 13, 1942, Serial No.
461,859. Divided and this application March
31, 1943, Serial No. 481,262

5 Claims. (Cl. 137—144)

The invention relates to a valve mechanism, and particularly to a unitary valve mechanism useful for controlling the operation of a pair of hydraulic pistons. It has heretofore been proposed to employ a pair of hydraulic pistons for controlling the orientation and elevation of a certain driven mechanism, with a separate valve for each piston. Also, connections are provided for admitting fluid under pressure to either side of each piston with the other side connected to the exhaust.

An object of the present invention is to provide a unitary valve mechanism having a common actuating member for independently or conjointly operating a plurality of valves for admitting pressure to either side of both pistons with the other side connected to exhaust. Hence both the orientation and elevation of the driven member can be controlled by means of the common valve actuator.

Another object of the invention is to reduce the number of machined parts, and hence reduce the weight and cost of valve mechanism having a plurality of valves operated by one handle.

Another object of the invention is to simplify and improve the valve mechanism for a valve assembly which is particularly suited for use in quadruplicate in a double 4-way valve having two pairs of valved passages (one pair for each hydraulic cylinder to be controlled), a high pressure inlet, and an outlet.

More particularly, the invention relates to an improved valve head for a double acting cam actuator for the valves.

For further details of the invention reference may be made to the drawing wherein Fig. 1 is a vertical sectional view on a broken line through the valve mechanism of this invention.

Fig. 2 is a partial sectional view on line 2—2 of Fig. 1, looking in the direction of the arrows.

I provide a handle 12 which may partake of two kinds of movements for independently or simultaneously operating the two pairs of passages 8—9, 10—11, and for connecting either passage in such pair to the high-pressure inlet not shown, with the other thereof connected to the outlet not shown. The manner in which this is accomplished, will be more readily apparent in connection with the drawings. As shown in Figs. 1 and 2 the valve casing 19 has a vertical cylindrical bore 38 which extends from the bottom of the casing 19 through the neck 18 where this bore is enlarged as indicated at 39. The bore 38 serves to house the lower end of the double

acting cam shaft or actuating member 17 and it also serves as a well into which the four double reciprocating valves 41, 42, 43 and 44 discharge, the bore or cam well 38 communicating with the outlet not shown. Fluid under pressure in the passage 47 is supplied to either of the two valves 41, 42 while the other thereof is serving to exhaust fluid from the low pressure side of the piston which it serves. Passage 48 for a similar purpose supplies fluid under pressure to the valves 43, 44.

As before stated, the valves 41—44 are selectively operated in pairs by imparting two kinds of movements to the handle 12. This will now be described in further detail.

Handle 12 can rotate on its own axis as it is supported in suitable bearings 13 and 14 in a cap 4. As the middle portion of handle 12 is offset to provide a crank 15 which is connected through a pitman 16 to the cam shaft 17, the cam shaft 17 is moved up or down when the handle 12 is rotated on its own axis in one direction or the other. Also handle 12, together with cap 4, crank 15, pitman 16 and cam shaft 17 constitute a valve head and are rotatable as a unit about a vertical central axis through valve 1 and through cam shaft 17, as cap 4 is rotatably carried by the neck 18 of the valve casing 19.

Cap 4 is split on a horizontal plane through handle 12, and its top piece 20 and bottom piece 21 are secured together by bolts 22. The bottom piece 21 of the cap 4 has a cylindrical extension 23 which extends into and concentric with the neck 18. Extension 23 has a cylindrical bore 24 in which the cam shaft 17 has a rotary and sliding fit. An intermediate portion of cam shaft 17 is cut away as indicated at 25. Extension 23 has a rotary fit in the cap 26 secured by screw threads 27 to the top of neck 18, and held in position by the lock ring 28. Suitable packing 29 is provided between the top of cap 26 and the extension 23. Between the extension 23 and the neck 18 are arranged two spaced ball-bearings 30 and 31. The bottom of cap 26 bears on the ball-bearing 30, which in turn bears on a sleeve 32 which is frictionally held to the outside of extension 33. The bottom of sleeve 32 rests on a lock ring 33 in the outside of extension 23, and lock ring 33 rests on bearing 31, while the latter rests on the enlarged upper end 34 of sleeve 35 which has a reduced section 36 fitting in the bore 38 in the valve casing 19. Thus the lock ring 33 and associated parts, prevents lengthwise or axial movement of extension 23 in either direction.

The cam shaft 17 is elongated with the upper end 56 making a rotary and sliding fit in the bore 24, the intermediate portion 57 making a rotary and sliding fit in the extension 23 and in the sleeve 35, and with the lower end 58 making a rotary and sliding fit in sleeve 59. Sleeves 35 and 59 are hardened ground and lapped steel bushings pressed in the bore 38. The bottom of bore 38 may be closed by a felt washer 60 and a cover cap 61 having a small aperture 62 to relieve the air pressure below the lower end 58 of valve stem 17. The intermediate cam shaft portion 57 may have a sealing ring 63 and the lower end 58 may have a sealing ring 64.

The lower end of passage 47 is sealed by a screw plug 65 and the lower end of passage 45 is sealed by a screw plug 66. Bearing in mind that the section in Fig. 1 is taken on a broken line, the bore 49 in a horizontal plane is laterally separated with respect to the bore 50, in order to bring their respective valve assemblies 41 and 42 at different operating positions on the cam 67 which is formed on approximately the left half of the cam shaft 17 between the shaft portions 57 and 58 as seen in Fig. 1. The bores 51 and 52 are in vertical alignment so as to bring their respective valve assemblies 43 and 44 in alignment with respect to the right half of the cam 67 where the latter is provided with two oppositely facing conical portions 68 and 69, the axes of these conical portions 68 and 69 being coaxial with the longitudinal axis of the cam shaft 17.

Each of the four valve assemblies 41-44 is of the same construction. All of these valve assemblies 41-44 are parallel, as seen in a vertical plane, and they all extend into the central bore or well 38. The outer end of the bore 49 is threaded to receive a valve cage 71 which can be adjusted lengthwise in the bore 49, it being held in adjusted position by a lock nut 72. Inside of the cage 71 is mounted a hollow tubular double acting reciprocating valve described and claimed in the companion case referred to hereafter. The piston 74 makes a sliding fit with the bore 76 at the right end of the cage 71. The valve assembly 41 at its right end is provided with a ball valve 78 to prevent fluid flow or exhaust through the inside of valve assembly 41 into bore 38 at certain times, and valve 78 at other times is permitted to move off from its seat to permit the exhaust liquid to flow through valve 73 into well 38 and then out through the outlet.

It will now be described how the valve assemblies 41-44 can be selectively operated in pairs. The cam 67, as indicated in Fig. 1, is convex and eccentric with respect to the longitudinal axis of the cam shaft 17, in planes at right angles to that axis while being equally distant from that axis in planes through that axis, with the result that the ball valve 78 for valve assembly 41 and the corresponding ball valve 91 for valve assembly 42 are not operated, or at least their operation is unaffected by reciprocating non-rotative movement of the cam 67. The left side of cam 67 is symmetrical about the plane of the drawing as shown in Fig. 1. Hence with cam 67 in neutral position, both of the ball valves 78 and 91 are closed against their seats.

Through rotative movement of cam 67 the double valve assemblies 41 and 42 as a pair can be operated without operating the valve assemblies 43 and 44, and that rotation of cam 67 in one direction makes connection 8 a supply line and connection 9 an exhaust, while rotation

in the other direction makes connection 9 a supply line and connection 8 an exhaust. Also cam 67 may be reciprocated but not rotated without affecting whatever relative positions assemblies 41 and 42 then have, movement in one direction serving to make connection 10 a supply line and 11 an exhaust, while straight-line movement in the other direction reverses the connections. Also the amount of rotation or longitudinal movement of cam shaft 17 determines the extent of the opening of the poppet valve such as 78, 80 and hence the amount of fluid under pressure being supplied can be adjusted. Also it is apparent that the cam 67 may have any desired rotary adjustment without disturbing the then existing longitudinal adjustment, and vice versa, or it may have simultaneously rotary and longitudinal adjustments at the same or different rates.

This application is a division of S. N. 461,859 filed October 13, 1942 for "Valve," which describes and claims the valve assembly. The multiple valve is described and claimed in S. N. 481,261, filed March 31, 1943.

It will be apparent that various modifications may be made in the invention without departing from the spirit of the following claims.

I claim:

1. A valve comprising a casing having a neck, said neck having a comparatively large bore merging into a smaller bore in said casing, a shoulder inside of said neck at the junction of said bores, a rotatable sleeve in said neck, a cap threaded in said neck and having a central aperture rotatably supporting said sleeve, a ball-bearing between said sleeve and said neck, said shoulder supporting the bottom of said ball-bearing, a lock ring on said sleeve supported by the top of said ball-bearing, spacer means between said lock ring and said cap, and a valve stem slidably fitting said sleeve, also slidably and rotatably fitting said casing bore, and a handle pivotally mounted on said sleeve for rotating and sliding said valve stem.

2. A valve comprising a valve casing having a neck, a sleeve fitted in the bottom of said neck, a valve head having a depending cylindrical member coaxial with said sleeve and having a bore substantially the same diameter as the inside of said sleeve, a double acting cam having portions having a sliding and rotating fit in said sleeve and said bore, means carried by said valve head for reciprocating said cam, a bearing cap having an aperture rotatably supporting said cylindrical portion, a ball-bearing between said cylindrical portion and the inside of said neck and supported by said sleeve, a lock ring on said cylindrical portion supported by said ball bearing, a spacer sleeve on said cylindrical portion and supported by said lock ring, a second ball-bearing between said cylindrical portion and said neck and supported by said spacer sleeve, and means for securing said cap to said sleeve, with said cap retaining said second ball-bearing against said spacer sleeve and the latter against said lock ring to prevent withdrawal of said cylindrical member from said neck while permitting rotation thereof.

3. In valve mechanism, a casing having a neck, a sleeve, and spaced ball bearings rotatably supporting said sleeve in said neck, a control stem slidably fitting in said sleeve, longitudinal cam means and transverse cam means on said control stem, a handle for rotating said sleeve, a

crank connection between said control stem and said handle for reciprocating said valve stem, and bearings in said sleeve supporting said handle for rotation about an axis crosswise of the direction of sliding movement of said control stem.

4. In valve mechanism, a casing having a neck and a well, a rotatable sleeve in said neck, spaced fixed sleeves in said well, the bore of said rotatable sleeve and said spaced sleeves being substantially the same, a control stem having a 10 piston portion fitting each of said fixed and rotatable sleeves, a handle, spaced bearings on said rotatable sleeve supporting said handle across said control stem, and a crank connection inside of said sleeve between said handle and said 15 control stem.

5. In valve mechanism, a casing having a neck and a well, said neck having a comparatively large bore merging into a smaller bore of said well, a rotatable sleeve in said large bore of said neck, a fixed sleeve in said smaller bore of said well at one end of said rotatable sleeve, the bore of said rotatable sleeve and said fixed sleeve being substantially the same, a control stem, said control stem fitting each of said sleeves, a handle, spaced bearings on said rotatable sleeve supporting said handle across said control stem, and a crank connection inside of said sleeve between said handle and said control stem.
